STRAND WINDING MACHINE

William E. Mahoney, Pawtucket, R. I., assignor to
Premier Thread Company, a corporation of
Rhode Island

Application July 30, 1936, Serial No. 93,403

11 Claims. (Cl. 242—43)

This invention relates to a strand winding machine, and more particularly to a mechanism for the formation of a package with a tapered end; and the invention has for one of its objects the provision of mechanism in which bobbins having varying tapered bases may be utilized without re-adjustment of the machine.

Another object of the invention is the provision of an arrangement whereby a part of the machine may be accurately set with reference to the traversing mechanism for the determination of the movement of the package so that bobbins having bases of somewhat varying dimensions may be used without re-adjustment of the machine, which dimensions heretofore had been considered necessary to be uniform.

Another object of the invention is the utilization of the pull on the thread in winding the same on the package for advancing the package axially, in the formation of the build of the strand on the package.

Another object of the invention is to control the build of the package from the surface of the bobbin base upon which the strand is to build so that the movement of the package will follow any variations of the angles of the surface of the base upon which the strand is to build and thereby prevent any cave-ins or interlocking of the strand in the package which might occur during any irregularities of the surface of the base upon which the strand builds.

Another object of the invention is the provision of a mechanism which may be used without re-adjustment for winding packages having a tapered barrel portion and a more greatly tapered base, which, due to differences in sizes, which readily occur, possibly from shrinkage or contraction, have heretofore required repeated adjustments to such an extent as to render tapered end cone-shaped packages unuseable from a practical standpoint.

With these and other objects in view, the invention consists of certain novel features of construction, as will be more fully described, and particularly pointed out in the appended claims.

In the accompanying drawings:

Fig. 1 is an end elevation of a portion of a winding machine upon which my invention is mounted;

Fig. 2 is a perspective view of the mandrel and bobbin mounted thereon with the thread guide and the bobbin control arm showing the strand as just commencing to be wound on the bobbin;

Fig. 3 is a perspective view similar to Fig. 2,

showing the bobbin as substantially filled with the strand wound thereon;

Fig. 4 is a sectional view through the winding mandrel showing a bobbin thereon and the relative positions of the thread guide and a control arm for the movement of the bobbin;

Fig. 5 is a sectional view on substantially line 5—5 of Fig. 4;

Fig. 6 is a perspective view of the sleeve upon which the bobbin is mounted;

Fig. 7 is a sectional view on line 7—7 of Fig. 6;

Fig. 8 is a perspective view of one part of the mandrel;

Fig. 9 is a sectional view showing the control arm as arranged in a single plane to show the relation of the parts;

Fig. 10 is a sectional view on line 10—10 of Fig. 9, showing the latch for locking the control arm out of contact with the package;

Fig. 11 is a sectional view illustrating a modified form of bobbin as positioned on the mandrel for providing a conical package with a tapered end;

Fig. 12 is an elevational view of modified form of mandrel showing in section a portion of the machine in which the same is mounted;

Fig. 13 is a sectional view of a portion of the machine showing the helical slot as located between bearings for the spindle.

Heretofore, in the use of a strand winding machine where it has been desired to wind a package with a tapered top, a tapered base has been provided and the machine adjusted to advance the cop upon which the strand was wound so that the strand would fill up upon the tapered base and form a correspondingly tapered end at the top. A mechanism for accomplishing this purpose is illustrated in the patent to Bosworth, No. 1,953,641, dated April 3, 1934. One of the

troubles experienced with the apparatus shown in this patent and other similar apparatus which controls the axial movement of the cop upon which the strand was wound in response to the increase of the diameter of the package, is that the packages must be accurately positioned upon the winding mandrel, and the yarn must be initially accurately placed upon the package, or else some one must adjust the machine so that this condition will occur. Further, there may be some

irregularities in the tapered face consisting in a variation of angle of the base which may cause locking in of the yarn of the package or a hollow at the base; and in order to avoid such undesirable conditions, I provide a means for positively

30

35

40

45

50

55

tending to feed the package axially and then hold the same back by a stop which engages the tapered base, and thus the traverse of the yarn follows this base to control its build; and the following is a more detailed description of the present means by which these advantageous results may be accomplished:

With reference to the drawings, it is unnecessary to illustrate in detail the usual parts of the winding machine of such construction as appears in a series of patents owned by the Universal Winding Machine Company, Foster Machine Co., and others, one of the essentials of such a machine being that it have a positive driven spindle. In Fig. 1 I have indicated the end of one such winding machine, the body of which is designated 10 having a stud 11 extending therefrom upon which is rockably mounted a frame 12. A counter-weight 13 at one end of this frame tends to swing the same to a vertical position. The thread guide consisting of a porcelain disk 14 with a notch 15 therein and an arm 16 with a porcelain member 17 having an opening 18 are carried by this frame and guides the strand as it builds up its diameter on the bobbin. The body 10 of the machine is provided with an arc-shaped member 19 against which a friction rod 20 pivoted as at 21 to the frame 12 is adapted to bear during the winding operation.

It is of course understood that the above merely represents some of the well-known parts of one make of machine to which my invention may be applied, other winding machines being equally substitutable therefor. My invention may be added as an attachment to machines now in use as well as being built into new machines.

The mandrel upon which the bobbin is mounted is designated generally 25 and is fixed to the rotatably mounted spindle 26 in the machine. This 40 mandrel consists of an arbor 27 and a sleeve 28 which has a bore 29 of a size larger than the external diameter of the arbor 27 so as to be rotatable thereon; and in order that a relative rotation of the sleeve and arbor will cause an advancement of the sleeve along the arbor, I have provided a stud 30 and generally helical slot connection between them. The stud may be in either part and the slot in the other part. In the form shown in Figs. 1 to 8 inclusive, this stud 50 30 is on the arbor 27 and the helical slot 31 is in the sleeve 28. A bobbin abutment collar 32 is secured upon the sleeve at some suitable location and is held in such position by means of a set screw 33. The sleeve 28 is grooved as at 34 55 and resilient bowed wires 35 are located within these grooves to be compressed by the positioning of the barrel portion 37 of the bobbin on the sleeve to hold the bobbin securely in position thereon. The bobbin is also provided with a conical base 38.

It is desirable in the trade to wind threads, strands, filaments, wire, or other like material upon bobbins or containers in such a manner that the completed package will have a tapered outer end and a hollow inner or basal tapered end that is in substantial parallelism with the outer end, and this hollow taper is wound against a tapering base as 38 of the bobbin to support the same. Accordingly, it has been usual to provide some mechanism which would positively advance the bobbin in accordance with a predetermined known taper of the base, and should there be any variation in the base the full desired supporting function thereof would fail. I, however, 70 advance the bobbin by means of the helical slot

and pin connection, which I have above described, which advancement occurs due to the pull of the thread as it is wound on the bobbin; and I retard such advancement by a feeler engaging with the tapered base of the bobbin so that regardless of the taper of the base my mechanism for control will operate to properly advance the bobbin, and in this manner I obtain a tapered end which corresponds exactly with the shape of the tapered base which is used as a pattern and guide for the advancement of the bobbin.

The control mechanism consists of an arm 40 which is securely mounted on the frame 10 of the machine by means of a bolt 41 extending through the boss 42 of this arm. The upper end of the 15 arm is also provided with a boss 43 threaded as at 44 into which the threaded portion 45 of a shaft 46 is mounted and held against rotation by the check nut 47. An arm 48 has its tubular base portion 49 rotatably mounted on the shaft 20 46 with one end abutting the shoulder 50 and a knob 51 secured to the shaft by set screw 52 engaging the other end of this tubular base. A spring 53 having one end 54 locked in the tubular base of the arm and the other end 55 locked in the knob 51 tends to swing the arm 48 about the shaft 46 as a center. The tension on the spring 53 may be varied by turning the knob 25 about the shaft 46 and then securing it by the set screw 52 in the position to which it is rotated. 30 At the outer end of the arm 48 I have provided a threaded opening 56 in which there is provided a threaded member 57 held in position by the check nut 58. Into one end of this threaded member 57 I mount the stud 59 by means of the 35 reduced threaded portion 60 providing a shoulder 61 to abut against the end of the member 57; and upon this stud is a bushing 62 and a contact roller feeler member 63 both held by means of the head 64 of the stud 59.

This roller 63 engages the tapered bobbin base 38 and prevents axial movement of the bobbin therealong. As the strand builds up on the bobbin increasing its diameter the control roller or feeler member 63 is moved outwardly from the center of the mandrel, thereby permitting the bobbin to advance incrementally and thus causing the taper 66 to be formed at the outer end of the package as the advancement gradually takes place. It is of course understood that the strand 50 67 which is wound upon the bobbin passes through the guides 17 and 14 and is traversed in such a manner as to form the wind desired; that which is shown is sometimes called a "cross wind" package and is one familiar to those skilled in the art; several different winds, however, may be used in connection with the invention, the particular wind being immaterial.

I have referred to the slot 31 as being helical. I have found, however, that a pitch of a greater 60 advancing power is desirable at the commencement of the winding of the strand upon the bobbin than after the strand has packed up sufficiently to gather weight and inertia of itself; and accordingly, rather than make the slot of 65 the same pitch along its length I commence the slot at a certain pitch and then increase this pitch to provide less power of advancement as the package builds up in mass. This pitch which is used for the slot must bear a certain balanced 70 relation to the spring 53 for holding the arm over to cause the contact member to control the advance of the sleeve, as will be readily apparent that a pitch of too great a power would overcome the power of the spring 53 to act as a stop and 75

control the advance of the bobbin, or vice versa, the spring might be of sufficient power to overcome the tendency for advancement of the helical slot along the mandrel. Accordingly, I have found that a slot which will have one revolution in approximately twelve inches is satisfactory and I can control advancement of the package by a spring of tolerable strength, the spring, of course, may be varied in order to apply more or less tension on the feeler member, and of course the pitch of the slot may be varied which may be advisable for different weights of strands wound or other variations necessary to compensate for. It will also be apparent that instead of the use of a spring for tending to move the stop into engagement with the tapered face of the package, I may utilize a weight for this purpose which may be adjusted as to the force which it will exert. In order to withdraw the feeler or contact member from the operation of the spring 53 to urge it into working position, the arm 48 may be retracted and a latch 85 dropped into the notch 86 in the tubular base 49 of this arm to hold it against the action of this spring.

25 In some cases instead of having the helical slot in the sleeve upon which the bobbin is mounted, I may have a tubular member 75 with a helical slot 76 therein mounted in the spindle 26 and an arbor 77 having a pin 78 thereon located 30 in the slot 76 with a collar 79 on the arbor. The bobbin will then be mounted on the arbor 77 against the collar 79 and the axial movement will be caused by the relative rotation of the parts 75 and 77 due to the pull of the thread.

35 Instead of the mandrel being an attachment, as in Fig. 12, I may bore out the spindle 26 as at 85 where it extends through the bearings 86 of the machine. The arbor 87 is located and may rotate in this bore 85. A generally helical slot 40 88 will be provided in the spindle 26 and a pin 89 secured to the arbor extends into the slot 88 so that when relative rotation takes place of the arbor and spindle the arbor will be advanced with reference to the spindle. The amount of advance will be governed by the length of the slot. The arbor 87 is of a larger size as 89 beyond the end 90 of the spindle, and an adjustable collar 91 on this larger portion serves as an abutment 45 for the bobbin mounting member. The opening 50 92 may be utilized to secure the arbor 87 against movement with reference to the spindle 26 if a straight wind is desired.

When it is desired to wind a bobbin having a tapered base 80 and a tapered barrel portion 81 I provide an attachment 82 of a taper corresponding to the inner shape of the barrel 81 and mount the same securely on the sleeve 28 by means of the set screw 83, this member 82 having bow wires 84 therein for the securing of the barrel 81 in position. In this manner a package which is tapered along its body portion and more sharply tapered at its end may be formed. When a tapered package is provided the feeler roll 63 will also be tapered to conform to the taper of the barrel and thus provide for a more uniform and distributed pressure thereon.

When preparing to wind a package, this machine is set so that the contact point 70 of the control or feeler member is in line with the delivery point of the yarn so that the yarn will engage the juncture of the base 38 and the cylindrical barrel portion 37 or the tapered barrel 81 of the bobbin for the start of the first layer of the strand; in other words, the point 70 and the 75 guide 14 are located in a plane at right angles

to the axis of the mandrel. So long as this occurs, it is immaterial just where the bobbin is positioned on the mandrel, as the mandrel will feed the bobbin forward as soon as the machine starts. Therefore, the distance between the juncture of the base 38 and the end of the barrel 37 or 81 of the bobbin which contacts the collar 32 is immaterial; and it is also immaterial at what taper the base is made relative to the barrel portion of the bobbin.

10 The contact member is preferably tapered as at 69 at an angle such as will fit along the taper of the base of the bobbin, although not essentially so. However, it is considered that if minor irregularities exist in the base that the 15 broader contact surface will tend to provide a smoother tapered end than where the contact member is of such a narrow dimension as to follow such small changes in taper.

Another feature of this construction is that 20 should it be desired to provide a straight end wind as distinguished from a tapered end wind, the adjustment of the machine is easily made by loosening the set screw 33 and adjusting the collar 32 if necessary and then placing a set 25 screw in the threaded opening 90 (Fig. 4) to bind the sleeve 28 against sliding on the arbor 27.

20 The foregoing description is directed solely towards the construction illustrated, but I desire it to be understood that I reserve the privilege of 30 resorting to all the mechanical changes to which the device is susceptible, the invention being defined and limited only by the terms of the appended claims.

I claim:

1. A strand winding machine for a tapered base bobbin consisting of a revolvable mandrel, a strand guide to present the strand to be wound, means relatively to traverse said strand guide along the mandrel in the winding of successive 40 layers upon a bobbin, means for moving the strand mass axially of the mandrel as wound, means engaging the tapered bobbin base for retarding said axial movement, and means operative in response to the building of the strand 45 mass to incrementally relieve said retarding means whereby the bobbin and mass thereon axially moves along the mandrel.

2. A strand winding machine for a tapered base bobbin consisting of a revolvable mandrel, 50 a strand guide to present the strand to be wound, means relatively to traverse said strand guide along the mandrel in the winding of successive layers upon a bobbin, means for moving the strand mass axially of the mandrel as wound, 55 means engaging the tapered bobbin base and bearing constantly upon the forming mass for retarding said axial movement and responsive to the building of the strand mass to incrementally relieve said retarding means whereby the bobbin and mass thereon axially moves along the mandrel.

3. A strand winding machine for a tapered base bobbin consisting of a revolvable mandrel, a strand guide to present the strand to be wound, 65 means relatively to traverse said strand guide along the mandrel in the winding of successive layers, means for moving the strand mass axially of the mandrel as wound, and means in contact with the base for following the shape of the base 70 of the bobbin and controlling therefrom the axial advancement of the bobbin and strand mass thereon.

4. A strand winding machine for a tapered base bobbin consisting of a revolvable mandrel, a 75

strand guide to present the strand to be wound, means relatively to traverse said strand guide along the mandrel in the winding of successive layers, means for moving the strand mass axially of the mandrel as wound, and a member engaging the forming strand mass and the tapered bobbin base to block the axial advancement of the strand mass along the mandrel, said building mass forcing the member outwardly to incrementally relieve the means for blocking said axial advancement, whereby the advancement is controlled by the tapered base regardless of its taper or contour.

5. A strand winding machine for a tapered base bobbin consisting of a revolvable mandrel, a strand guide to present the strand to be wound, means relatively to traverse said strand guide along the mandrel in the winding of successive layers, means for moving the strand mass axially of the mandrel as wound, and a member provided with resilient means urging it toward the forming strand mass for contact therewith and into a position to be engaged by the bobbin base as advanced along said mandrel to block axial advancement of the strand mass, said building mass forcing the member outwardly to incrementally relieve the means for blocking said axial advancement, whereby the advancement is controlled by the tapered base regardless of its taper or contour.

6. A strand winding machine for a tapered base bobbin consisting of a revolvable mandrel, a strand guide to present the strand to be wound, means relatively to traverse said strand guide along the mandrel in the winding of successive layers, means for moving the strand mass axially of the mandrel as wound, an arm having a rolling contact member, and resilient means urging said arm toward the forming strand mass for contact therewith and into a position to be engaged by the tapered bobbin base as advanced along the mandrel to block axial advancement of the strand mass, said building mass forcing the member outwardly to incrementally relieve the means for blocking said axial advancement, whereby the advancement is controlled by the tapered base regardless of its taper or contour.

7. A strand winding machine for a tapered base bobbin consisting of a revolvable mandrel, a strand guide to present the strand to be wound, means relatively to traverse said strand guide along the mandrel in the winding of successive layers, means for moving the strand mass axially of the mandrel as wound, a member provided with resilient means urging it toward the forming strand mass for contact therewith and into a position to be engaged by the bobbin base as advanced along said mandrel to block axial advancement of the strand mass, said building mass forcing the member outwardly to incrementally relieve the means for blocking said axial advancement, whereby the advancement is controlled by the tapered base regardless of its taper or contour, said resilient means being ad-

justable for varying the urge toward the strand mass.

8. A strand winding machine for a tapered base bobbin consisting of a revolvable mandrel, a strand guide to present the strand to be wound, means relatively to traverse said strand guide along the mandrel in the winding of successive layers, means for moving the strand mass axially of the mandrel as wound, and a member provided with resilient means urging it toward the forming strand mass for contact therewith and into a position to be engaged by the bobbin base as advanced along said mandrel to block axial advancement of the strand mass, said building mass forcing the member outwardly to incrementally relieve the means for blocking said axial advancement, whereby the advancement is controlled by the tapered base regardless of its taper or contour, said member also being adjustable axially of the mandrel to vary its position with reference to the positioning of the bobbin in a desired location on the mandrel.

9. A strand winding machine for a tapered base bobbin consisting of a revolvable mandrel, a strand guide to present the strand to be wound, means relatively to traverse said strand guide along the mandrel in the winding of successive layers, means responsive to the pull of the strand for moving the strand mass axially of the mandrel as wound, and means for retarding said axial movement and responsive to the building of the strand mass to incrementally relieve said retarding means whereby the mass axially moves along the mandrel.

10. A strand winding machine for a tapered base bobbin consisting of a revolvable mandrel, a strand guide to present the strand to be wound, means relatively to traverse said strand guide along the mandrel in the winding of successive layers, means responsive to the pull of the strand for moving the strand mass axially of the mandrel as wound including a part in which the mass is mounted rotatable relative to the mandrel and helical slot and pin connection between said mandrel and part relatively rotatable thereon, and means for retarding said axial movement and responsive to the building of the strand mass to incrementally relieve said retarding means whereby the mass axially moves along the mandrel.

11. A strand winding machine for a tapered base bobbin consisting of a revolvable mandrel, a strand guide to present the strand to be wound, means relatively to traverse said strand guide along the mandrel in the winding of successive layers, a sleeve on the mandrel, said sleeve and mandrel having respectively a helical slot and pin connection between them whereby a relative rotation causes an axial movement, and means in contact and following the tapered base of the bobbin as a pattern to control the advance of the strand mass along the mandrel.

WILLIAM E. MAHONEY.
